SEAMING APPARATUS

Peter Bogner, London, England, assignor to Saml. Hanson & Son Limited, London, England, a British company

Application February 28, 1938, Serial No. 192,989
In Great Britain November 9, 1937

4 Claims. (Cl. 113—19)

This invention consists of improvements in apparatus for making tins or sheet metal containers, cans and the like of the well known kind having a closure member provided with a marginal flange which is interfolded with an out-turned flange at the end of the can-body so that the marginal flange lies outside and embraces the outer wall of the can-body. Interfolding of the marginal flange of the closure and the can-body may be effected in several different ways but the present invention is directed to interfolding by the known operation of double or multiple seaming.

In the manufacture of canisters there is a well-established practice in attaching the closure to the can-body. This is effected by the use of a seam-forming machine which normally embodies a flat cylindrical chuck or anvil which lies within the dished portion of the closure to contact with the walls thereof and a roller or rollers arranged to engage with the marginal flange of the closure, the roller or rollers being rotatable on a spindle parallel to the axis of the container, which spindle is moved round the axis of the container, means being provided also to move the roller or rollers towards the can-body to form and to compress the seam.

The invention relates particularly to the manufacture of tins or sheet metal containers, cans and the like which are provided with an opening device comprising a wire which is housed within the pressed circumferential portion with an end protruding through the closure to the outside thereof to provide a purchase for opening the can without the use of a separate can-ripping instrument. Such opening-wires are commonly termed "rip-wires" and will so be referred to hereinafter.

More specifically the present invention is concerned with apparatus for seaming end-closures of the form constituting the subject-matter of my copending United States Patent application Serial No. 191,230 filed February 18, 1938, and which comprise a central depression to fit within the mouth of a can to be closed and a marginal portion constituting a flange for interfolding with the can-body characterised by the fact that the material of the closure is continued outwardly from the depression in the form of a narrow shoulder reaching to a wire-supporting wall which extends to the marginal flange and upon which a rip-wire is intended to be held inside the closure, and an opening to the outside of the closure is formed close to the said wall

through which the rip-wire may pass for ripping the closure open.

An object of the invention is to provide apparatus for seaming end-closures of the form described which may readily be applied to existing seam-forming machinery.

A further object of the invention is to provide seaming apparatus by means of which the disposition of the rip-wire within a ridge which affords said wire-supporting wall and the compression of the ridge during the seaming operation can be determined with exactitude.

A further object of the invention is to provide apparatus whereby precise alignment between the chuck and seaming roller or rollers can readily be secured and maintained during seaming.

The invention accordingly comprises in apparatus for seaming end-closures of the form described, the employment of a chuck which fits the depression in the end-closure to support the side-walls thereof during seaming, the said chuck having a peripheral step which is shaped to overlap the narrow shoulder between the depressed central portion and the ridge of the closure so as to maintain the shoulder and to support the inner wall of the ridge during the seaming operation.

According to a further feature of the invention a seaming roller is arranged to be brought into engagement with the marginal flange of the closure to produce interfolding thereof with the can-body and guiding means is also provided constituted by a flange on the chuck to overlap and to engage with the seaming roller so as to align the said parts during the seaming operation. Alternatively, the guiding means may be constituted by a flange on the seaming roller to overlap and to engage with the chuck so as to align the said parts during the seaming operation.

According to another form of the invention the guiding means may comprise a channel in and around the side wall of the seaming roller together with a flange on the chuck fitting the said channel so as to align the said parts during the seaming operation. Again, the channel may be provided in and around the side wall of the chuck and the flange be provided on the seaming roller.

Further objects, advantages and features of the invention will appear from the following description taken in conjunction with the accompanying drawings which illustrate in diagrammatic form several different embodiments of the present invention.

Referring to the drawings:

Figure 1 is a fragmentary, central sectional, view through one form of chuck and seaming roller showing the manner in which the said parts co-operate in interfolding the marginal flange of the closure with the can-body in the first stage of the seam-forming operation;

Figure 2 shows the final stage of the seam-forming operation with the same chuck as Figure 1 and another seaming roller specially adapted for the final closing of the seam;

Figure 3 illustrates the first operation with a chuck and a roller of an alternative form;

Figure 4 shows the final stage of the seaming operation utilising the modified chuck of Figure 3 and a seaming roller shaped for final closing of the seam;

Figure 5 illustrates the first operation utilising a chuck and roller similar to the construction of Figure 3 but having a roller which is modified to secure more exact guidance with the chuck;

Figure 6 shows the first operation utilising a first operation roller similar to that of Figure 1 in conjunction with a further modified form of chuck; and

Figure 7 illustrates a further modification of a first-operation seaming roller.

It is to be understood that in all the figures of the accompanying drawings the dimensions of the parts are much exaggerated and that for the sake of clarity substantial clearances are shown between certain of the parts although no such clearances occur in practice.

Referring to Figure 1, 11 represents a can-body having a flared lip 12 at its end. The end-closure is of the form which constitutes the subject-matter of my copending United States Patent application Serial No. 191,230 filed February 18, 1938 and includes a depressed central portion 13, an upstanding wall 14, a marginal flange 15 and a hollow ridge 16 upset within the flange 15 to provide a space 17 which houses a rip-wire 18. The ridge 16 is spaced somewhat from the upper edge of the wall 14 so as to divide off a portion of the flange 15 as a narrow inner shoulder 19. It will be appreciated that the said parts extend around the whole of the end-closure and can-body as described in my said copending application. For the purposes of this invention, it is thought sufficient, however, to describe and to show only the present fragmentary portion of the closure and can-body.

As described in the said prior application, the interior of the ridge 16 is shaped to present a non-divergent substantially cylindrical inner wall 20 which is joined to a curved outer-wall 21, the said walls joining substantially at right-angles and the metal of the ridge 16 being reduced in thickness at the line of joining at the two walls to provide a line of weakness in the ridge to facilitate ripping of the metal by the rip-wire 18 when the can is to be opened.

A chuck 22 fits within the central depressed portion 13 and lies in contact with the wall 14 to support the latter during the seaming operation. According to the present invention the chuck 22 is provided with a marginal or peripheral step 23 which overlaps the shoulder 19 and fits against the inner face of the ridge 16.

A first-operation seaming roller 24 is mounted for rotation about a spindle 25 which in turn may be mounted so as to revolve planet-wise about the chuck 22 (which is stationary) as in the conventional can-seaming machinery. Al-

ternatively, the chuck, closure and can-body may revolve upon its own axis and roller 24 rotate about the spindle 25. In either case, the seaming roller is pressed into engagement with the marginal flange of the closure by means not shown.

In Figure 1 the seaming roller is shown as provided with a continuous seaming surface 26 running into the underside of a flange 27 which extends over the top of the chuck 22 in contact with the upper surface of the step 23. The underside of the flange 27 is inclined away slightly from the plane at right-angles to the spindle 25 so as to diverge upwardly in the form of a very shallow cone. The contour of the seaming surface 26 is similar to the conventional form of surface for a first-operation roller except that in the present case the surface is slightly wider than that of the normal seaming roller in order to accommodate the increased height of the chuck 22 occasioned by use of the step portion 23.

The seaming roller is shown in a position relatively to the chuck which occurs approximately half-way through the first seaming operation. The seaming operation is carried out in the usual way.

Prior to seaming, the marginal flange 15 is flat and is provided with a downwardly curled edge, the lip 12 then lies against the flat underside of the flange. At the commencement of the seaming operation the seaming roller spins against the curled edge of the outstretched flange 15 and the seaming surface 26 deflects the edge of the flange 15 downwards and simultaneously curls the lip 12 until upon continued advancement of the seaming roller the said parts become interfolded to the extent shown in the drawings. During seaming, the marginal flange 15 is considerably stressed and the ridge 16 conveniently strengthens the marginal flange 15 and, in conjunction with the flange 27 of the roller, holds the said flange against buckling. At the same time the step 23 maintains the shoulder 19 and supports the inner face of the ridge 16 against the thrust of the seaming roller so that the rip-wire 18 is kept in its proper position at the top of the space 17. During the latter part of the first seaming operation the flange 27 of the roller overlaps the step 23 of the chuck 22 and serves to guide the roller to ensure rotation of the roller without any tendency for the roller to partake of rocking movement about an imaginary axis at right-angles to the spindle 25. The extent of advancement of the seaming roller during the first operation is such as to obtain practically complete interfolding of the parts 12 and 15; at the end of the first operation the bottom edge 28 of the seaming roller should lie closely adjacent to the can-body 12. During such time as the flange 27 is advancing across the step 23 the roller is being raised upwards slightly owing to the coning of the underside of the flange 27. Metal from the flange 15 is thereby fed up into the seam.

Figure 2 shows a final seaming roller 34 with the parts in the position which they assume soon after the beginning of the final seaming operation. The seaming roller is mounted for rotation on a spindle 35 and is provided with a seaming surface 36, a flange 37, and shallow conical underside for overlapping the chuck. The surface 36 is similar to the normal final operation seaming surface but is increased in depth to allow for the depth of the ridge 16. The seaming

roller is advanced to the left of the position shown until the seam closes completely. As in the first seaming operation the taper on the underside of the flange 37 causes the roller to rise slightly in reaching its final position so feeding more of the flange 15 into the space between the lip 12 and the can-body 11. In the finished seam the rip wire is located in the correct position for cutting through the apex of the ridge 16 and is also completely isolated from the contents of the can being held snugly in the compressed ridge. The shoulder 19 is also maintained until the finish of the seam.

If desired, the chuck employed during the first operation may be changed prior to the second or final operation for one having a step portion 23 which is shallower than that of Figure 1. The chain-line 38 of Figure 2 indicates a convenient height for such a different height chuck. When employing a chuck of this form the finished seam can be reduced in depth as compared with that produced in accordance with Figure 2 since the flange 37 of the seaming roller is able to act directly upon the top of the ridge to feed metal into the side of the seam from which it becomes spun up into the seam.

In the embodiment of Figure 3 the chuck comprises a body portion 42 provided with a step 43 which is extended as a flange 44 to overlap a first-operation seaming roller 45. The seaming surface of roller 45 is in this case divided into a major portion 46 which is shaped to spin the marginal flange 15 into interfolded relationship with the lip 12 of the can-body and a minor portion 47 to act separately upon the outer-wall of the ridge 16 towards the end of the first operation. The flange 44 takes the place of the flange 21 of the seaming roller of Figure 1 and is made with a flat underside to contact with a flat face at the top of the seaming roller so as accurately to align the roller with the chuck during seaming. The slight ridge on the seaming roller providing the transition between surfaces 46 and 47 acts, towards the end of the first operation, upon the bottom of the outer-wall of the ridge 16 and causes the inner wall 21 of the ridge 16 to close towards the wall 20 so as to embrace the rip-wire to a greater extent than in previous constructions. The said ridge between the two surfaces 46 and 47 also acts upon the closure in the manner described just prior to the action of the surface 47 and the rip-wire is thereby held from slipping out of the ridge 16 under the action of the pressure applied from above by the surface 47.

In the construction of Figure 4, the chuck is similar to that of Figure 3, but the final seaming roller 55 is provided with a major seaming surface 56 joined to a minor seaming surface 57, the roller 55 being guided during the final operation by the flange 44 of the chuck. As in the construction of Figure 2 the surface 56 is of such a shape as to perform the final closing operation upon the seam, but in the present construction the minor seaming surface 57 acts separately upon the outer wall 21 of the ridge 16 to bring it in the finished seam to a position lying closely adjacent to the wall 20.

Figure 5 shows a modified form of first operation seaming roller which is generally in accordance with the construction of Figure 3 except that the upper end of the roller is continued as a flange 60 to over-lie the flange 44, on the chuck. The seaming roller of Figure 5 is thereby provided with a channel 61 having plane parallel sides and

the flange 44 of the chuck is such as to fit closely within the said channel so as to guide the seaming roller accurately in alignment with the chuck during the first seaming operation.

It will be understood that the construction of Figure 5 may equally be applied to a final seaming roller of the kind shown in Figure 4.

In Figure 6 there is shown a first operation seaming roller similar to that of Figure 1 but in this instance the chuck is provided with a flange 70 which overlies but is spaced apart from a stepped portion 71 thereby providing a circumferential channel 72 within which the flange 73 upon the seaming roller may work. The upper and lower sides of the flange 73 are plane-parallel as are also the upper and lower walls of the channel 72 in the chuck and exact alignment of the seaming roller with the chuck may thereby be secured in the seaming operation. As in Figure 5, this modified construction may equally be applied to a final seaming roller of the kind shown in Figure 2 but as in Figure 6 the underside of the flange upon the seaming roller will be flat.

Figure 7 shows a further modified embodiment of a first operation seaming roller which includes a major seaming surface 80 and a minor seaming surface 81 as in Figure 3 but in this instance the seaming roller itself carries a flange 82 which overlaps the upper surface of the chuck and serves to guide the seaming roller during the seaming operation. It will be understood that the embodiment of Figure 7 may equally be applied to a final seaming of roller of the form shown in Figure 4.

The invention is not limited to the precise details of construction, arrangement and method of operation herein set forth as it is clear that various changes and modifications may be made therein without departing from the essential features of the invention. Thus, as an instance of one such change it is pointed out that in the constructional form of the invention described with reference to Figure 6 the seaming roller may be modified so as to include major and minor seaming portions as described with reference to Figure 3 or Figure 4.

In the foregoing specification the expression "closure" is intended to include either of the ends of the can-body. In other words, the closure carrying the wire may be applied to the can-body before the canister is filled, so as to constitute the bottom; or it may be applied after the canister is filled so as to constitute the top.

I claim:

1. In apparatus for seaming an end-closure of the form described having the wire-supporting wall afforded by one wall of a hollow ridge, the combination comprising a chuck to fit the depression in the end-closure to support the side walls thereof during seaming, which chuck has a peripheral step shaped to engage the narrow shoulder and wire-supporting wall of the end-closure and to hold said shoulder and wall in place during seaming, and a seaming roller to engage the marginal flange of the end-closure for effecting seaming, which seaming roller is formed with a major seaming surface shaped to act on the marginal flange of the end-closure and a minor seaming surface disposed at the end of the major seaming surface as viewed in cross-section taken through the axis of the seaming roller, said minor seaming surface being arranged to cooperate with the peripheral step on the chuck to act upon the outer wall of the ridge

of the closure, and a flange on one of the parts constituted by the chuck and seaming roller which flange engages the other of said parts during seaming to support that portion of the closure which continues outwardly from the wire-supporting wall towards the periphery of the closure.

2. In apparatus for seaming an end-closure of the form described having the wire-supporting wall afforded by a wall of a hollow ridge, the combination comprising a chuck to fit the depression in the end closure to support the side walls thereof during seaming, which chuck includes a chuck body having its peripheral surface adapted to engage the side walls of said depression and a peripheral projection disposed beyond said peripheral surface and providing shoulder-engaging and wall-engaging surfaces to support respectively the narrow shoulder and the wire-supporting wall of the end-closure during seaming, a seaming roller for engaging the marginal flange of the end-closure, which seaming roller has concave annular major and minor seaming surfaces adjoining one another, with the major seaming surface aligned with the sides of the chuck body and with the minor seaming surface aligned with the peripheral projection carried by the chuck, a flange on one of the parts constituted by the chuck and seaming roller, which flange engages the other of said parts during seaming and extends immediately adjacent to the peripheral projection on the chuck and serves to maintain said seaming roller with its major and minor seaming surfaces in alignment with said chuck body and peripheral projection.

3. In apparatus for seaming an end-closure of the form described having the wire-supporting wall afforded by a wall of a hollow ridge, the combination comprising a chuck to engage and support the side walls of the depression in the end-closure, which chuck includes a chuck body having its peripheral surface adapted to engage

the side walls of said depression and a peripheral projection disposed beyond said peripheral surface and providing shoulder-engaging and wall-engaging surfaces to support respectively the narrow shoulder and the wire-supporting wall of the end-closure during seaming, a seaming roller for engaging the marginal flange of the end-closure, which seaming roller has concave annular major and minor seaming surfaces adjoining one another, with the major seaming surface aligned with the sides of the chuck body and with the minor seaming surface aligned with the peripheral projection carried by the chuck, a flange on one of the parts constituted by the chuck and seaming roller, which flange engages the other of said parts during seaming and extends immediately adjacent to the peripheral projection on the chuck and serves to maintain said seaming roller with its major and minor seaming surfaces in alignment with said chuck body and peripheral projection.

4. In apparatus for seaming an end closure of the form described, the combination comprising a chuck having a body portion of shape to fit within and support the sidewalls of the depression of the end closure and a peripheral projection extending outwardly from the top of the body portion to engage and support the shoulder and wire-supporting wall of the end closure, a seaming roller to engage the marginal flange of the end closure and in cooperation with the chuck to seam the end closure, said roller having a seaming surface aligned with and equal in depth to the depth of the peripheral surfaces of the body portion of the chuck and of the projection, and a flange on one of the parts constituted by the chuck and seaming roller said flange overlapping and engaging the other of said parts during seaming, said flange extending immediately adjacent to the peripheral projection on the chuck.

PETER BOGNER.
